JOINT FOR LEVELS AND SQUARES

Filed Aug. 11, 1937

UNITED STATES PATENT OFFICE

2,183,086

JOINT FOR LEVELS AND SQUARES

David E. Semon, Jacksonville, Fla.

Application August 11, 1937, Serial No. 158,613

1 Claim. (Cl. 287—14)

My invention relates to new and useful improvements in a combination folding brickmason's tool and has for its primary object, to provide a tool of this character which will combine a spirit level, try square, and straightedge and the various measurement rules as used by brickmasons.

The spirit levels as used by brickmasons at the present time are generally of one piece of material and four-feet long and due to the length, it is impossible for the brickmason to carry the level in a bag containing his tools. I am aware, that attempts have been made to provide a sectional folding spirit level, and so far as I am aware the attempts have failed, for the reason that the sections comprising the level have to be completely disconnected to be knocked down.

It is an object of my invention to provide a brickmason's tool comprising sections which may be folded without dismembering or disconnecting the sections that make up the level.

A further object of my invention is the provision of hinge pins and novel means for mounting and holding the hinge pins in position for swivel movement.

A further object of my invention is the provision of novel swivel hinge pins so mounted in the section, that one section may be swung at right angles to the adjacent section or sections, the sections being provided with means on the front and back faces and on the ends for insuring proper alignment and locking engagement when connected together.

A further object of my invention is the provision of horizontal and vertical bubble glasses in the sections, providing leveling means either as a spirit level or try square.

A still further object of the present invention is the provision of the various measurement rules generally used by brickmasons, the measurement scales being provided on the front and back faces of the sections.

With the foregoing and other objects in view, the invention consists in the novel arrangement and combination of parts hereinafter more specifically claimed and illustrated in the accompanying drawing, in which:

Figure 1 is a view in side elevation of my improved folding spirit level and try square with the sections in assembled position.

Figure 2 is a fragmentary top plan view illustrating sections formed into a try square.

Figure 3 is a fragmentary vertical sectional view illustrating in detail the hinge pin and means for holding the hinge pin for swivel movement.

Figure 4 is a fragmentary vertical sectional view

of a modified form of my invention and illustrating in detail the hinge pins, the means for holding the hinge pins in position for swivel movement, the means for proper alignment of the sections when in assembled position, and the means for bringing the sections together and securely locking them.

Figure 5 is a top plan view of a modified form of my invention illustrated in Figure 4 and illustrating one of the sections swung at right angles to the other in open position, and the means for locking the sections together to form a try square.

Figure 6 is a fragmentary side elevational view of another modified form of my invention.

Figure 7 is a fragmentary vertical sectional view of the modified form of my invention as illustrated in Figure 6.

Figure 8 is a sectional view taken on line 8—8 of Figure 6.

Figure 9 is a top plan view of my invention in a partially folded position and illustrating how sections may be folded without being detached from each other.

Figure 10 is a sectional view of the locking nut and illustrating the arrangement of bores therein.

My improved brickmason's level as illustrated in Figure 1 of the drawing is designated by the numeral 11 and it comprises a plurality of sections designated by the letters A, B and C and it is to be noted that on the front face at the bottom of each section I provide numerical indicia 12, 13 and 14, representing inches. At this point I would have it understood that the measurement rule indicia may be placed on the back face also of the sections. On the sections A, B and C, the indicia as indicated, 12 from 0 to 16; 13 from 17 to 32; and 14 from 33 to 48, the sections in assembled position as in Figure 1, making a level

four feet in length, which is the length generally used by brickmasons, however I do not wish to limit my invention to any determined length for the reason that due to the novel arrangement of parts, the device may be made up of any desired number of sections greater than illustrated. For the purpose of illustration on the front face of section A, at the top edge I have shown a number of lines designated by the numeral 15, and these lines represent the well known brickmason's

measuring rule well known in the art, and each section is to be provided with the indicia of the brickmason's rule.

The sections may be made of any suitable material, such as wood or metal. The openings and

arms of the sections as indicated in the drawing, Figures 1 to 5, I deem it proper that the openings and arms, for proper description, be described individually.

5 One end of section A is provided with an elongated opening 16 and due to this opening arms 17 and 18 are formed. Section B at both of its ends is provided with elongated openings 19 and 20, and due to these openings arms 21 and 22 on 10 the left hand end are formed, and arms 23 and 24 are formed on the right hand end; and section C is provided with an elongated opening 25 having arms 26 and 27.

Arms 17 and 18 of section A are each provided 15 with an aperture 28 and it is to be noted that a portion of each aperture has an enlarged portion 29 that forms a recess 30 for a purpose to be later described. On the front and rear faces of the arms 17 and 18 are sockets 31, and on the end 20 faces sockets 32. The abutting end faces of the arms 21 and 22 of section B are provided with pins 33 that are adapted for engagement with the sockets 31 and 32 in the arms 17 and 18 of section A. The arms 21 and 22 are each provided 25 with an aperture 34 each aperture having an enlarged portion 35 that forms a recess 36.

Arms 23 and 24 on the right hand end of section B, on the front and rear faces are provided with sockets 37, and on the end faces with sockets 38. Each of the arms 23 and 24 are provided with an aperture 39, each aperture having enlarged portion 40, that forms a recess 41. The abutting end faces of arms 26 and 27 of section C are provided with pins 42 that are adapted 35 to engage the sockets 37 and 38 of section B. The arms 26 and 27 are each provided with an aperture 43, each aperture having an enlarged portion 44 that forms a recess 45.

Due to the positioning of the sockets and pins 40 in and on the arms of the respective sections, I provide a means whereby section C may be fixedly secured to section B, either in horizontal alignment or at right angles thereto, as illustrated in Figure 2.

45 Within the openings 16, 19, 20 and 25 are mounted hinge pins which I designate by the numeral 46 as illustrated in Figure 1 and in detail in Figure 3, the hinge pins 46 are provided with bores 47 and 48 and a horizontal bore 49 for a purpose to be later described. The hinge pins 46 are held in position for swivel movement 50 between the respective arms of the sections by pintles 50 that are mounted in the apertures 28 34, 39 and 43 of the respective arms and these 55 pintles engage the bores 47 and 48 in the hinge pins. The pintles 50 are held against casual displacement in the respective arms by a ring spring 51 that is seated in the enlarged recessed portions 30, 36, 41 and 45.

60 Interposed between the hinge pins 46 as illustrated in the various views of the drawing, is a lock nut 52 having a head 53 and a shaft 54, the shaft being provided at its opposite ends with right and left hand screw threads 55 that engage the horizontal bore 49 in the hinge pins 46. The head 53 is provided with bores 56 as illustrated in detail in Figure 10 of the drawing for the reception of any suitable means for turning the lock-nut 52, to lock the sections as illustrated 65 70 in Figure 1 rigidly together.

In Figures 4 and 5 of the drawing, I have illustrated a modified form of my invention, in which the section A' is provided with an elongated opening 57 forming arms 58 and 59, each 75 of the arms having an aperture 60, and sockets

61 on the front and rear faces, and sockets 62 on the end faces. Section B' is provided with an elongated opening 63 forming arms 64 and 65, each arm being provided with an aperture 66 and pins 67 on the end faces adapted for engagement 5 with the sockets 61 and 62. Within the openings 68 and 69, and between the respective arms of the sections A' and B' are mounted hinge pins 68 having threaded bores 69 and 70 and a horizontally threaded bore 71. The hinge pins 68 are 10 held in position between the arms for swivel movement by screws 72 having an enlarged head 73 that engages the apertures 68 and 69 in each of the arms of the sections, the threaded shank 74 of the screws 72 engage the threaded bores 69 and 70 in the hinge pins 68. The lock nut 52 is interposed between the hinge pins of sections A' and B' and as the lock-nut has been previously described, description at this point is 15 deemed not necessary.

In Figures 6, 7 and 8, I have illustrated another modified form of my invention in which section A'' has a cut out portion 75 and section B'' a cut out portion 76 and at this point I would have it understood that section B'' has its 20 opposite end cut out although I have not shown same. The sections A'' and B'' are provided around their edges with protective strip means 77 and 78 that may be of any suitable material such as copper, aluminum or the like, the strip 30 means 77 and 78 being secured to the sections A'' and B'' by screws 79. The strip means 77 and 78 at their ends each have enlarged portions 80 and 81. The inner faces 82 and 83 of the strip means 77 and 78 abut against the end faces 84 and 85 of section A''. Likewise, the end faces 86 and 87 of the strip means 78 abut against the end faces 88 and 89 of section B''. The enlarged end portions 80 and 81 of the strip means 35 are each provided with bores 90 and 91 for a 40 purpose to be later described. The front, back and end faces of the end portions of strip 77 are each provided with a wedge shaped groove 92 and it is to be noted the groove is cut approximately one-half the thickness of the enlarged 45 portion 80. The end faces 81' of the strip means 78 of section B'' are provided with a wedge shaped rib 93 adapted to engage the wedge shaped grooves 92. Within the bores 90 and 91 are mounted for swivel movement hinge pins 94 that are 50 provided with a horizontal bore 95. Interposed between the hinge pins 94 is a lock nut 52 which has been previously described.

In the operation of my device, assuming the device is folded as in Figure 9, it is only necessary 55 to straighten the sections out in a horizontal plane, this being very readily done, due to the fact that each section has mounted therein for swivel movement the hinge pins 46 that are connected together by a lock-nut 52 having a threaded 60 shaft 54 with right and left hand threads, the pintles 50 acting as bearings for the swivel movement of the hinge pins. When the sections are in alignment, and ready to be securely locked as in Figure 1, the head 53 of the lock nut is rotated 65 and the provision of right and left hand threads on the shaft 54 draws the sections together and during the locking engagement the pins 33 on section B engage the sockets 32 on section A and pins 42 on section C engage the sockets 38 on section B, thus making a perfect alignment of the sections and preventing the sections from coming out of alignment when the sections are in locked engagement. To insure rigid locking engagement of the sections, a nail or some other 70 75

instrument may be inserted in the bores 56 of the head and pressure exerted. If it is desired to form the device into a try square, as illustrated in Figures 2 and 5 it is merely necessary to swing section B at right angles to section A, or section C at right angles to section B, then tighten up on the lock-nut until the sections are brought together, the pins 42 will engage the sockets 37.

In the operation of the modified form of the invention illustrated in Figures 4 and 5, the swivel movement of the hinge pins is the same as in Figure 1, except that the head 73 of the pintal 72 serves as the bearing for the hinge pins.

In the operation of the modified form of the invention illustrated in Figures 6, 7 and 8, the ends of the hinge pins 94 are seated in the bores 90 and 91 and swivel in the bores.

While the principles of the invention will always be adhered to, the invention is susceptible to

certain changes and modifications, and I do not wish to limit myself to the exact structures, and changes may be made without departing from the spirit or scope of the invention.

What I claim is:

In a level comprising separable sections adapted to be disposed in alignment or angular relation to each other, means for hingedly connecting said sections together comprising pins pivotally mounted in recesses in the ends of the abutting sections, a right and left hand threaded member 10 engaging threaded apertures in said pivoted pins and complementary interengaging locking means carried by the ends and sides of said sections, said threaded member providing means for drawing the interlocking means into engagement when the sections have been arranged in selected position.

DAVID E. SEMON.
